CLAIM

The ornamental design for a smart watch, as shown and described.

DESCRIPTION

FIG. 1 is a top front perspective view of a smart watch showing my new design.

FIG. 2 is a top front left side elevation view of the smart watch.

FIG. 3 is a top front right side elevation view of the smart watch.

FIG. 4 is a top right perspective view of smart watch.

FIG. 5 is a top left perspective view of smart watch.

FIG. 6 is a top back left side perspective view of smart watch; and,

FIG. 7 is a top back right side perspective view of smart watch.

The oblique shade lines in the figures show a transparent, reflective, or shiny surface and not surface ornamentation.
